E. OPFERKUCK

WATER CIRCULATING SYSTEM FOR INTERNAL COMBUSTION ENGINES

Filed June 19, 1922

UNITED STATES PATENT OFFICE.

EMIL OPFERKUCK, OF SPRINGFIELD, OHIO, ASSIGNOR TO THE SUPERIOR GAS ENGINE COMPANY, OF SPRINGFIELD, OHIO, A CORPORATION OF OHIO.

WATER-CIRCULATING SYSTEM FOR INTERNAL-COMBUSTION ENGINES.

Application filed June 19, 1922. Serial No. 569,477.

To all whom it may concern:

Be it known that I, EMIL OPFERKUCK, a citizen of the United States, residing at Springfield, in the county of Clark and 5 State of Ohio, have invented certain new and useful Improvements in Water-Circulating Systems for Internal-Combustion Engines, of which the following is a specification.

10 This invention relates to improvements in internal combustion engines of the type in which air for scavenging and fuel mixture purposes is compressed by the working stroke of the piston, and it particularly relates 15 to means for utilizing the compressed air for creating a more effective circulation of cooling water through the water jacket of the engine.

The object of my invention is to provide, 20 in an engine which employs the thermo-syphon system of circulation for the cooling water, means for assisting the circulation of the water which consists in utilizing the air pressure created by the piston.

25 A more specific object of the invention is to utilize this air pressure for the purpose stated in a way which will be extremely simple in character and effective in operation.

30 In the drawings, the view is a longitudinal section of so much of an internal combustion engine as is necessary to illustrate the improvements, showing my invention applied thereto.

The engine shown is of the two-cycle type, 1 representing the cylinder; 2 the hollow piston; 3 the water jacket about the piston; 4 the removable head having the 35 combustion chamber, hot ignition member 40 and fuel nozzle 6; 7 the water jacket for the head; 8 a removable chambered plate which communicates with the water jackets 3 and 7; 9 an air chamber about the rear 45 end of the cylinder; 10 an air supply port in which is located a check valve (not shown); 10 an air inlet port leading from the air chamber to the cylinder; 12 an exhaust port leading from the cylinder to the 50 water jacket exhaust pipe 13; 14 water supply pipes leading from the tank 15 to the water jacket; 16, and 17 and 18 sections of the water discharge pipe leading from the

water jacket to the water tank and connected by the tees 18 and 19. 55

Connected with the air chamber 9 is a vertical pipe 21, the upper end of which communicates with the body 22 of a regulating stop check valve in which 23 represents the valve seat and 24 the valve, 60 the hollow stem 23' of which receives the lower end of a threaded stem which may be adjusted to regulate the opening movement of the valve. Leading from the body 22 is a horizontal pipe 26 which communicates with the tee 19. Communicating with the upper end of the tee 20 is a riser or standpipe 27 having its upper end open to the atmosphere. 65

The operation of the device is as follows: In the event the parts become too hot, which sometimes happens under certain running conditions of the engine, the valve 22 is released from its seat by turning out the threaded stem whereupon, upon 70 each working stroke of the piston, which compresses air in the chamber 9, air will be forced through the pipes 21 and 26 and valve body 22 into the water discharge pipe, thus applying air pressure to the water and 75 increasing the rapidity of circulation thereof, this air escaping from the riser or standpipe 27. By adjusting the threaded stem 25, the amount of air pressure may be 80 nicely regulated so as to secure the necessary rapidity of circulation of the cooling water and thereby maintain the temperature of the engine at the most efficient degree of heat. The valve 24 acts as a check 85 valve to prevent back pressure and the entrance of water into the air chamber 9. 90

Having thus described my invention, I claim:

1. In an internal combustion engine, the combination, with the cylinder, of a water jacket, an air chamber located about one end of the cylinder in which air is compressed upon each working stroke of the piston, a water discharge pipe leading from the jacket, and an air pipe forming a communication between said air chamber and said water pipe, and means for preventing back pressure in said air pipe and for regulating the amount of air passing there-through. 95

2. In an internal combustion engine, the 100

combination, with the cylinder, of a water jacket, an air chamber located about one end of the cylinder in which air is compressed upon each working stroke of the piston, a water discharge pipe leading from the jacket, and an air pipe forming a communication between said air chamber and

said water pipe, and a valve in said air pipe to prevent back pressure and to regulate the amount of air passing therethrough. 10

In testimony whereof, I have hereunto set my hand this 13th day of June, 1922.

EMIL OPFERKUCK.
